CLAIM

The ornamental design for a tub for bathing, as shown and described.

DESCRIPTION

FIG. 1 is a perspective view taken from the top, front and right side of a tub for bathing embodying my new design;

FIG. 2 is a top plan view thereof;

FIG. 3 is a cross-sectional view taken on line 3—3 of FIG. 2; and,

FIG. 4 is a cross-sectional view taken on line 4—4 of FIG. 2.

The fragmentary broken line representations of a bathroom island installation deck in FIG. 1, and of openings in FIGS. 1, 2 and 3 are for the purpose of illustration only and form no part of the claimed design.
